202,711

NOVELTY ITEM OR THE LIKE FOR GOLFERS

Fred C. Philpitt, 5324 Westpath Way, Bethesda, Md.

Filed Oct. 5, 1962, Ser. No. 71,994

Term of patent 14 years

(Cl. D29—28)

FIGURE 2 is a view of one side of the novelty item or the like for golfers, all six sides being identical in appearance to the side shown in FIGURE 2.

I claim:

The ornamental design for a novelty item or the like for golfers, substantially as shown and described.
